(57) **CLAIM**

The ornamental design for combination infant car seat and stroller, as shown and described.

DESCRIPTION

FIG. 1 is a perspective view showing the upper right front of the combination infant car seat and stroller, the upper left front view being a mirror image thereof; and,
FIG. 2 is a perspective view showing the upper right rear of the combination infant car seat and stroller, the upper left rear view being a mirror image thereof.

The bottom surface of the combination infant car seat and stroller, while not featureless, is disclaimed and forms no part of this design.
